(21) Appl. No.: **29/312,160**

The ornamental design for an opener for a bottle of sparkling wine, as shown and described.

(22) Filed: **Oct. 2, 2008**

DESCRIPTION

(30) **Foreign Application Priority Data**

Apr. 9, 2008 (JP) 2008-009105

FIG. 1 is a front elevational view of an opener for a bottle of sparkling wine showing my new design.

(51) **LOC (9) Cl.** **07-99**

FIG. 2 is a rear elevational view thereof;

(52) **U.S. Cl.** **D8/40**

FIG. 3 is a top plan view thereof;

(58) **Field of Classification Search** D7/680;
D8/14, 18, 33–43; 7/151–156; 81/3.07,
81/3.09, 3.2, 3.27, 3.29, 3.35, 3.37, 3.4, 3.44,
81/3.45, 3.48, 3.49, 3.55

FIG. 4 is a bottom plan view thereof;

See application file for complete search history.

FIG. 5 is a left side elevational view thereof;

(56) **References Cited**

FIG. 6 is a right side elevational view thereof;

FIG. 7 is a perspective view thereof; and,

FIG. 8 is a front elevational view thereof showing my new design in an open state.

U.S. PATENT DOCUMENTS

The ornamental design of the present invention relates to an opener for removing a cork from a bottle of sparkling wine such as a champagne bottle, which can be used by first removing the wire cover around the bottle, then inserting, into the cork, protrusions provided on the inner sides of the sandwiching and holding part of the opener, and removing the cork while rotating the opener.
